SUBMARINE RESCUE DEVICE

Henry L. Pegg, St. Paul, Minn.

Application April 29, 1933, Serial No. 668,497

7 Claims. (Cl. 61—69)

My invention relates to submarine vessels in general and more particularly to improvements in submarine rescue ships of the class used to save lives of persons in sunken submarines.

5 A main feature is to provide means for gaining access to the interior of such vessels, said means comprising certain mechanical devices hereinafter fully set forth. The invention consists of further improvements on my submarine 10 rescue ship patent, Serial No. 312,455, filed October 15, 1928, and which issued Feb. 10, 1931, Patent Number 1,792,118.

In the accompanying drawing,—

15 Fig. 1 is a side elevation, partly in section, of a rescue ship of my improved design and operatively connected with an outlet of a submarine, the latter shown in cross section.

Fig. 2 is an enlarged longitudinal section of approximately the left half of Fig. 1.

20 Fig. 3 is a face view of a manhole or outlet of a submarine as provided for rescue purposes.

Fig. 4 is an outer end elevation of an inner connecting cylinder of my device, in a preferred form.

25 Fig. 5 is a side elevation of Fig. 4.

Referring to the drawing by reference numerals, 10 designates the usually elongated hull of a submarine in this case to be designated as the rescue ship and 11 designates a sunken 30 submarine or other vessel resting on the sea bed 12. Only one end of the rescue ship is shown and is provided with adjustable, tubular means for making frictional and mechanical contact with the sunken vessel for access to the interior 35 of the latter.

Propelling means for the rescue ship and manipulating means are provided as needed for manipulating the rescue ship but do not comprise a part of this invention.

40 The nose of ship 10 is provided with an integral tubular outlet 13, the outer end of which

may be flared semi-spherically as 13F to provide one member of a universal ball-joint of which the other member is fitted within 13F and 45 designated as 14F, being a part of a tubular rear outlet 14 of a cylindrical head 15. The latter is large enough for several persons to occupy it or such persons may readily pass from it through tubes 14 and 13 to the interior of the rescue

50 ship. 16 is a tube integral of housing 15 and projecting forward therefrom concentrically. It is provided near its inner end with female threads 16T adapted to be engaged by corresponding male threads 25T of a so-called contact tube 25, said

55 latter tube being within the tube 16 and reciprocable therein on the threads. Tube 25 extends forwardly beyond tube 16 and its inner end is provided with a perimetral ring-gear 17. Said gear is engaged by a drive pinion 18 rotatable on a pin 19 fixed in housing 15, said drive pinion be-

ing rotatable by any suitable power means designated as a crank 20. Obviously, rotation of the drive pinion rotates gear 17 which moves the contact tube forward or back within outlet 16 as desired and for a purpose presently to be described.

21 is a water tight door normally closing the inner end of contact tube 16 and is hinged at 22. This door has a central opening covered by a glass 23 through which an operator in housing 15 may observe when the tube 25 has been brought into water tight contact with a submarine (see Fig. 2).

24 is an exterior tubular shell concentric of and slideable on the tube 16 as on an inner flange 75 24F. Between the inner end of said shell 24 and the adjacent part of housing 15 may be fixed a ring 26A of resilient material about tube 16 to provide a bumper. The outer perimeter of shell 24 may have a removable rubber rim or flange 26 or equivalent means to provide yieldable but water tight contact against a flat surface 27 which is concentric of a submarine hatch way or outlet of which the opening is designated 28 (see Figs. 1 and 2).

The shell 24 is best designated as 80 85 a bumper as it makes initial contact when the rescue ship is manipulated to a position where it is possible to make contact concentric of the hatchway. Obviously, contact may be made in almost any required angular position according to the position of the hatchway of the sunken vessel with which contact is desired. It is assumed that submarines are provided with a number of such outlets which may at present be of about the construction shown but it is further

90 95 assumed that for the purposes of my invention submarines and other vessels shall be provided with a number of such outlets, the cover of which (not shown) may be such as to be removable from either the interior of the submarine or from my device.

The means for manipulating my device to various angles relative to the hull of the rescue ship have been fully disclosed in my previous patent application, now issuing. Said means in this case

105 are shown as consisting of a series of drums 29 on outlet 13 rotated by suitable power means (not shown) and each of which has a cable 30 connected to housing 14 as at 31.

32 are a series of piston rods operable from the interior of housing 14 and projecting forward therefrom, their forward ends provided each with a contact member 33 which in this case is preferably a magnet adapted to contact with the hull of the submarine exteriorly of the hatchway thereof and exteriorly of the bumper cylinder 24. Current to magnetize the members 33 is applied when initial contact is made, by means not shown, the pistons 32P of the piston rods 32 being subsequently reciprocated by any suitable controlled

pressure means as air or steam, within the cylinders 34, to draw the housing forcibly toward the sunken vessel and causing cylinder 24 to forcibly bear against face 27 and establish water tight contact.

Further mechanical means presently to be described are used to cause water tight contact of inner cylinder 25 about the hatchway 28. These means comprise a number of circularly spaced fingers 35 fixed on the outer end of cylinder 25, each said finger extending outwardly and forwardly in arcuate and angular position from the cylinder and adapted to engage in correspondingly spaced eye-members 36, each fixed in a plane at right angles to the exterior face of the hatchway frame outwardly of its opening 28. Assuming that contact of cylinder 24 and magnets 33 has first been made, concentric of opening 28, it will now be readily understood that 20 the inner cylinder is moved forwardly by rotating the pinion 18, turning cylinder 24 on its threads which causes the cylinder to move forward, the fingers 35 moving in a circle and coming into frictional engagement with the stationary eyes 36. Obviously, the forward end of cylinder 25 is thus brought into frictional contact with the outer face of the hatchway concentric of opening 28 and near it.

In Figs. 2 and 3 this face is designated 37 and is recessed for an inserted ring of resilient material 38. Disengagement of the fingers from the eyes or loops 36 is of course attained by simply reversing the rotary movement of cylinder 25.

I have now fully described my improved submarine contact device in a preferred embodiment thereof. It is obvious that a number of modifications may be made without departing from the scope and spirit of the invention. For example, the friction fingers 35 may be interiorly of the cylinder 25 and the loops 36 located accordingly. With frictional and magnetic contact made as above described about a hatch of a sunken submarine it is obvious that the interior of the latter is accessible through the tubular means 13, 14, 25 and the housing 15, from the rescue ship 10, and lives of men in the sunken ship can thus be saved and means provided to bring repair parts to the interior of the sunken vessel.

The safety door 21 with its glass 23 is of course not opened until it is observed through said glass when water tight contact has been made and it is safe to open it.

I claim:

1. In a submarine rescue ship comprising a submersible vessel provided at one end with a tubular extension communicating with its interior and having a universal joint for manipulation of the said extension to desired angular positions; said extension forward of the joint comprising a cylindrical housing with a fixed integral forwardly directed concentric cylinder, an outer shock absorbing cylindrical shell mounted to reciprocate on said cylinder and opening forwardly of it, an inner contact tube reciprocable and rotatable within the fixed cylinder, means on said contact tube adapted to frictionally engage the area of a hatchway frame of a vessel about its opening simultaneously with frictional contact of the shock absorbing cylinder outwardly thereof and means outwardly of the latter mounted to reciprocate in a direction longitudinally of the device to make frictional contact with a vessel exteriorly of the first described contact parts, said latter means comprising each, 70 and means outwardly of the latter mounted to reciprocate in a direction longitudinally of the device to make frictional contact with a vessel exteriorly of the first described contact parts.

2. The structure specified in claim 1 in which said inner contact cylinder means comprises the provision of male threads on its exterior and corresponding female threads provided in the concentric cylinder of the housing and means for 80 rotating the said contact tube to reciprocate it by said thread means to move the tube by means of said threads toward or away from contact with a vessel about the hatchway of the latter.

3. The structure specified in claim 1 in which said inner contact cylinder means comprises the provision of male threads on its exterior and corresponding female threads provided in the concentric cylinder of the housing and means for 85 rotating the said contact tube to reciprocate it by said thread means to move the tube by means of said threads toward or away from contact with a vessel about the hatchway of the latter and further of said contact means of the contact tube comprising a series of circularly spaced fingers 90 fixed on the outer end part of said tube, the said fingers projecting outwardly and forwardly in like angular planes and arcuate with relation to the curvature of the tube walls, eye members fixed in circular spaced relation to the hatchway 95 opening of said submarine, and said fingers of the contact tube adapted to simultaneously engage said eye members when the said tube is rotated.

4. The structure specified in claim 1 in which 100 said inner contact cylinder means comprises the provision of male threads on its exterior and corresponding female threads provided in the concentric cylinder of the housing and means for 105 rotating the said contact tube to reciprocate it by said thread means to move the tube by means of said threads toward or away from contact with a vessel about the hatchway of the latter, and a hinged lid mounted on the inner end of said contact tube to provide water tight closure therefor, and a transparent panel in said lid, and said lid accessible from within the main cylinder.

5. The structure specified in claim 1, and a ring 110 of resilient material on the outer rim of said shock absorbing shell.

6. The structure specified in claim 1 and a yieldable shock absorbing member mounted between the rear end of said shock absorbing shell and the adjacent wall of the main cylinder.

7. In a submarine rescue ship comprising a 120 submersible vessel provided at one end with a tubular extension communicating with its interior and having a universal joint for manipulation of the said extension to desired angular positions; said extension forward of the joint comprising a cylindrical housing with a fixed integral 125 forwardly directed concentric cylinder, an outer shock absorbing cylindrical shell mounted to reciprocate on said cylinder and opening forwardly of it, an inner contact tube reciprocable and rotatable within the fixed cylinder, means on said contact tube adapted to frictionally engage the area of a hatchway frame of a vessel about its opening simultaneously with frictional contact of the shock absorbing cylinder outwardly thereof and means outwardly of the latter mounted to reciprocate in a direction longitudinally of the device to make frictional contact with a vessel exteriorly of the first described contact parts, said latter means comprising each, 130 further, a contact member at the forward end of each reciprocable member and adapted to be magnetized when contact is made for the purpose set forth.
